ADAPTER FOR INCANDESCENT LIGHT BULB

Terry Hermanson, New York, N.Y., assignor to
Mr. Christmas Incorporated, New York, N.Y.

Filed Oct. 26, 1972, Ser. No. 301,148

Term of patent 14 years

Int. Cl. D13—03
U.S. Cl. D26—1 G

FIG. 1

FIG. 2

FIG. 3

FIG. 4

FIG. 1 is a perspective view of an adapter for incandescent light bulb showing my new design;

FIG. 2 is a side elevational view;

FIG. 3 is a second side elevational view with adapter rotated about its longitudinal axis 90° from the position shown in FIG. 2; and

FIG. 4 is an end elevational view corresponding to the left side of the adapter illustrated in FIG. 3.

I claim:

The ornamental design for an adapter for incandescent light bulb, as shown.
